To all whom it may concern:

Be it known that I, Russel Wright, a citizen of the United States of America, and a resident of the city of New York, Borough of Manhattan, county of New York, and State of New York, have invented the new, original, and ornamental Design for a Knife, of which the following is a specification, reference being had to the accompanying drawings, forming part thereof in which—

Fig. 1 is a top plan view of a knife, embodying my new design.

Fig. 2 is a side elevation thereof.

Fig. 3 is a bottom plan view of the knife.

Fig. 4 is a cross-sectional view taken on the line 4—4 of Fig. 1.

I claim:

The ornamental design for a knife, as shown.

RUSSEL WRIGHT.
